SURGICAL INSTRUMENT

Carl Willers, Chicago, Ill., assignor to Francis C. Kollath, Chicago, Ill.

Application August 6, 1942, Serial No. 453,837

13 Claims. (Cl. 30—231)

This invention relates to a surgical instrument and more particularly to surgical shears.

A primary object of the invention is the provision of improved surgical shears for removing casts, splints, bandages and like members from the body of a person without causing injury or pain to the person.

A further object is the provision of improved, hand operated surgical shears which are simple in construction, inexpensive to manufacture, easy to operate, and provide for heavy duty cutting without substantial injury or pain to the body of a patient.

A further object is the provision of surgical shears having a relatively flat plate member for guiding and supporting the shears during a cutting operation, the said plate member being adapted for insertion beneath a cast or the like and having the shearing or cutting elements arranged above the plate member.

A still further object is the provision of such shears in which the handle members for operating the shears are so positioned as to extend substantially perpendicular to the surface of the cast, or the like, being cut and to be entirely out of the way of an arm, leg, or other member having the shears applied thereto.

These and other objects and advantages of the invention will be apparent from the following description, the appended claims, and the accompanying drawing which illustrates a selected embodiment of the invention, and in which:

Fig. 1 is a perspective view of a surgical shearing instrument constructed in accordance with the present invention and illustrating the manner in which it may be applied to remove a cast or the like from the body of a person;

Fig. 2 is a side detail view of the shearing instrument of Fig. 1 partly in section, with certain of the operative parts shown in two positions by full and dashed lines;

Fig. 3 is a left hand end view of the shears shown in Fig. 2; and

Fig. 4 is a sectional detail taken on the line 4—4 of Fig. 2.

Referring to the drawing, the illustrated surgical instrument comprises a thin, resilient and relatively flat plate member 10, a pair of operating handles 11 and 12, a pair of stationary shear or cutting plates 13, and a pivotally mounted shearing or cutting member 14. The plate 10 provides a guide and supporting member for the shears and is adapted to be inserted between an article to be cut, such as a plaster cast, splint, bandage or the like, and a member on which the

article to be cut is supported, such as an arm, leg, or other part of the body of a person.

The handle 11 extends upwardly and substantially normal to the guide plate 10 and is suitably shaped and curved conveniently to fit the palm of the hand of an operator, as indicated at 15. Below the portion 15 the handle 11 comprises a flat plate portion 16 which is rigidly connected to the guide and supporting plate 10. Pins or lugs 17 extend downwardly from the plate portion 16 and pass through suitable openings provided in the guide and support plate 10, the lugs or pins 17 being riveted or swaged on the under side of the plate 10 rigidly to attach the handle 11 to the plate 10. Above the plate 10 the portion 16 of the handle 11 widens outwardly to provide a widened portion 18 to which the pair of stationary shear or cutting plates 13 are rigidly attached by means of rivets 19 or the like.

Each of the shearing plates 13 extends laterally of the handle 11 and generally parallel with the plate member 10, and comprises a lower shearing or cutting surface 20 and an upper curved surface 21. The plates 13 are also each provided with an upwardly turned nose portion 22 for freely guiding the shears into the member to be cut, and the nose portions 22 are interconnected by means of a pin 23 or the like more rigidly to support the forward ends of the shear plates 13.

The shearing or cutting member 14 is pivotally mounted between the shear plates 13 by means of a bolt 24 or the like which extends through suitable openings in the shear plates forwardly of the widened portion 18 of the handle 11. The handle 12 is rigidly attached to the cutting member 14 and in the illustrated embodiment forms an integral extension of a portion 25 of the cutting member 14.

The cutting member 14 together with its portion 25 is received between the shear plates 13 while the handle 12 extends upwardly above the upper portion 21 of the stationary shear plates. The handle 12 is suitably curved and shaped, as illustrated, conveniently to fit within the palm of the hand of an operator and, together with the portion 25, extends substantially laterally and perpendicular to the cutting member 14 and substantially normal to the guide and supporting plate 10.

The pivotally mounted cutting member 14 normally extends downwardly into the space between the shear plates 13 and guide plate 10, as illustrated by full lines in Fig. 2, and is urged into this position by means of a coiled spring 26

having upwardly extending legs 27 and 28. The spring 26 is positioned between the handles 11 and 12 and normally tends to separate the handles and to move the cutting member 14 downwardly with respect to the stationary shear plates 13. Any suitable means, such as a lug 29, may be provided for maintaining the spring 26 in proper position between the handles 11 and 12.

Outward movement of the handle 12 with respect to the handle 11 under action of the spring 26 is limited by engagement of the handle 12 with the upper portion 21 of the shear plates 13. This limiting movement is provided by means of shoulders 30 which bulge laterally outwardly, as best shown in Fig. 3, between the handle 12 and the portion 25 of the cutting member 14.

The cutting or shearing member 14 is also preferably provided with serrated teeth 31, as shown, better to enable the shears to cut through splints, casts, heavy bandages, and the like. The lower supporting and guide plate 10 is also preferably provided with an opening 32 within which the lower end of the cutter 14 is adapted to be received when the handles 11 and 12 and shear members 13 and 14 are separated by the spring 26.

In operation the guide and supporting plate 10 is adapted to be inserted between an article to be severed and a member on which the article is supported or attached. The handles 11 and 12 extend upwardly from the plate 10 and are substantially perpendicular and normal to the plate 10 and the article to be cut. Thus the operating handles for the shears are positioned so as to avoid any contact with either the article to be cut or a member supporting the article. The shears are readily operated by merely squeezing the handles together, as illustrated by dashed lines in Fig. 2, and then releasing the handles, the spring 26 serving to move the cutting element 14 to an open position with respect to the shearing plates 13.

Shears particularly adapted as a surgical instrument are accordingly provided. Thus, as shown in Fig. 1, the guide and supporting plate 10 may be inserted beneath a plaster cast, bandage or like member 33, and the shears provide for readily and simply cutting the member 33 without substantial injury or pain to an arm 34 or other part of a person's body.

Changes may be made in the form, construction and arrangement of parts without departing from the spirit of the invention or sacrificing any of its advantages, and the right is hereby reserved to make all such changes as fairly fall within the scope of the following claims.

The invention is hereby claimed as follows:

1. An instrument of the character described comprising a flexible plate member adapted for insertion beneath an article to be cut to provide for guiding and supporting the instrument during a cutting operation, cutting members positioned above said plate member and operatively attached to the plate member, and means including handles attached to said cutting members for operating the cutting members, said handles extending substantially normal to the surface of said flexible plate member and being adapted to be gripped in one hand of an operator to operate the cutter members by squeezing one handle towards the other.

2. An instrument of the character described comprising an elongated stationary cutting member, a cooperating pivotally mounted cutting

member, operating handles for said cutting members, and an elongated guide plate spaced below said stationary cutting member and extending generally parallel therewith, said pivotally mounted cutting member being operable within said space between the stationary cutting member and the guide plate to effect cutting by movement towards the stationary member and away from the guide plate.

3. An instrument of the character described comprising an elongated stationary cutting member, a cooperating cutting member pivotally mounted on said stationary cutting member, operating handles for said cutting members, and an elongated guide plate spaced below said stationary cutting member and extending generally parallel therewith, said pivotally mounted cutting member being operable within said space between the stationary cutting member and the guide plate to effect cutting by movement towards the stationary member and away from the guide plate.

4. An instrument of the character described comprising a guide plate member, an upstanding member attached to said guide plate member, a stationary shear plate attached to said upstanding member and extending generally parallel to said guide plate member in spaced relationship therewith, and a cooperating shear member pivotally mounted on said shear plate and operable within said space between the stationary shear plate and the guide plate member to effect cutting by movement towards the stationary plate and away from the guide plate.

5. An instrument of the character described comprising a guide plate member, an upstanding member attached to said guide plate member, a stationary shear plate attached to said upstanding member and extending generally parallel to said guide plate member in spaced relationship therewith, a cooperating shear member pivotally mounted on said shear plate and operable within said space between the stationary shear plate and the guide plate member to effect cutting by movement towards the stationary plate and away from the guide plate, an operating handle rigidly attached to said stationary shear plate and extending generally upwardly with respect to said guide plate member, and a second upwardly extending operating handle rigidly attached to said pivotally mounted shear member.

6. An instrument of the character described comprising a guide plate member, an upstanding member attached to said guide plate member, a stationary shear plate attached to said upstanding member and extending generally parallel to said guide plate member in spaced relationship therewith, a cooperating shear member pivotally mounted on said shear plate and operable within said space between the stationary shear plate and the guide plate member to effect cutting by movement towards the stationary plate and away from the guide plate, an operating handle rigidly attached to said stationary shear plate and extending generally upwardly with respect to said guide plate member, a second upwardly extending operating handle rigidly attached to said pivotally mounted shear member, and spring means for normally separating said stationary and pivotal shear members.

7. An instrument of the character described comprising a guide plate member, an upstanding member attached to said guide plate member, a pair of substantially parallel stationary shear

plates attached to said upstanding member and extending generally parallel to said guide plate member in spaced relationship therewith, a cooperating shear member pivotally mounted between said shear plates and operable within said space between the stationary shear plates and the guide plate member to effect cutting by movement towards the stationary plates and away from the guide plate, and operating handles connected to said stationary shear plates and said pivotally mounted shear member, said operating handles extending upwardly with respect to said guide plate member.

8. An instrument of the character described comprising a guide plate member, a handle member rigidly attached to said guide plate member and extending upwardly therefrom, a stationary shear member rigidly attached to said handle member and extending laterally thereof in spaced substantially parallel relationship with respect to said guide plate member, a cooperating shear member pivotally mounted on said stationary shear member for opening and closing movement with respect thereto, said pivotally mounted shear member being adapted to extend downwardly toward said guide plate member when opened, and a second handle member rigidly attached to said pivotally mounted shear member and extending upwardly with respect to said guide plate member.

9. An instrument of the character described comprising a guide plate member, a handle member rigidly attached to said guide plate member and extending upwardly therefrom, a stationary shear member rigidly attached to said handle member and extending laterally thereof in spaced substantially parallel relationship with respect to said guide plate member, a cooperating shear member pivotally mounted on said stationary shear member for opening and closing movement with respect thereto, said pivotally mounted shear member being adapted to extend downwardly toward said guide plate member when opened, a second handle member rigidly attached to said pivotally mounted shear member and extending upwardly with respect to said guide plate member, and said pivotally mounted shear member being provided with a plurality of serrations forming teeth on the upper side thereof.

10. An instrument of the character described comprising a guide plate member, a handle member rigidly attached to said guide plate member and extending upwardly therefrom, a stationary shear member rigidly attached to said handle member and extending laterally thereof in spaced substantially parallel relationship with respect to said guide plate member, a cooperating shear member pivotally mounted on said stationary shear member for opening and closing movement with respect thereto, said pivotally mounted shear member being adapted to extend downwardly toward said guide plate member when opened, a second handle member rigidly attached to said pivotally mounted shear member and extending upwardly with respect to said guide plate member, and spring means cooperating between said handle members normally to urge said pivotally mounted shear member to an open position.

11. An instrument of the character described comprising a guide plate member, a handle member rigidly attached to said guide plate member

and extending upwardly therefrom, a stationary shear member rigidly attached to said handle member and extending laterally thereof in spaced substantially parallel relationship with respect to said guide plate member, a cooperating shear member pivotally mounted on said stationary shear member for opening and closing movement with respect thereto, said pivotally mounted shear member being adapted to extend downwardly toward said guide plate member when opened, a second handle member rigidly attached to said pivotally mounted shear member and extending upwardly with respect to said guide plate member, spring means cooperating between said handle members normally to urge said pivotally mounted shear member to an open position, and means on said second handle member cooperating with said stationary shear member for limiting opening movement of the pivotally mounted shear member.

12. An instrument of the character described comprising a guide plate member, a handle member rigidly attached to said guide plate member and extending upwardly therefrom, a stationary shear member rigidly attached to said handle member and extending laterally thereof in spaced substantially parallel relationship with respect to said guide plate member, a cooperating shear member pivotally mounted on said stationary shear member for opening and closing movement with respect thereto, said pivotally mounted shear member being adapted to extend downwardly toward said guide plate member when opened, a second handle member rigidly attached to said pivotally mounted shear member and extending upwardly with respect to said guide plate member, spring means for normally urging said pivotally mounted shear member to an open position, means on said second handle member cooperating with said stationary shear member for limiting opening movement of the pivotally mounted shear member, and said guide plate member being provided with an opening for receiving the lower end of the pivotally mounted shear member when in open position.

13. An instrument of the character described comprising a guide plate member, a handle member rigidly attached to said guide plate member and extending upwardly therefrom, a pair of parallel stationary shear plates rigidly attached to said handle member and extending laterally thereof in spaced substantially parallel relationship with respect to said guide plate member, a cooperating shear member pivotally mounted between said stationary shear plates for opening and closing movement with respect thereto, said pivotally mounted shear member being adapted to extend downwardly toward said guide plate member when opened, a second handle member rigidly attached to said pivotally mounted shear member and extending upwardly with respect to said guide plate member, spring means cooperating between said handle members normally to urge said pivotally mounted shear member to an open position, means on said second handle member cooperating with said stationary shear plates for limiting opening movement of the pivotally mounted shear member, and said guide plate member being provided with an opening for receiving the lower end of the pivotally mounted shear member when in open position.

CARL WILLERS.
